UNITED STATES PATENT OFFICE.

GILSON C. STAATS, OF FOLSOM, PENNSYLVANIA, ASSIGNOR TO COMET RADIATOR COMPANY, OF PHILADELPHIA, PENNSYLVANIA, A CORPORATION OF PENNSYLVANIA.

RADIATOR.

Application filed September 24, 1925. Serial No. 53,223.

My invention relates to an improvement in radiators and more especially to radiators of the type adapted to be heated directly by gas.

5 Radiators of the type to which my invention pertains have, heretofore, not been wholly successful and have possessed a number of disadvantageous features, chief among which are that, in operation, a substantial 10 amount of pressure is developed which requires the provision of means for its relief and possesses an element of danger and that they are relatively uneconomical of fuel, and give out odor.

15 Now in accordance with my invention, I have provided a radiator adapted to be heated directly by gas or other suitable fuel, which will be entirely safe, an operation economical of fuel and of a high degree of 20 efficiency.

Further, in accordance with my invention I have produced a radiator of the type indicated in which a novel circulatory system is utilized and which is structurally laid 25 out on novel lines.

Having now indicated in a general way the nature and purpose of my invention, I will proceed to a detailed description thereof with reference to the accompanying 30 drawings in which there is illustrated a preferred embodiment and in which:

Figure 1, is a side elevation of a radiator embodying my invention.

Figure 2, is a side elevation of a modification of the radiator shown in Figure 1.

Figure 3, is a sectional view of the radiator shown in Figure 1.

Figure 4 is a view taken on line 4—4, Figure 3.

40 Figure 5 is a view taken on line 5—5, Figure 3.

The radiator embodying my invention comprises any desired number of sections, a centrally located section or sections being 45 in open communication with a heating chamber in which is positioned a burner. As shown in Figure 1, the radiator comprises seven sections, three central sections being in communication with a heating chamber, 50 while in Figure 2 the radiator comprises four sections, two central sections being in communication with the heating chamber. In the following description it will be understood that the radiator may be con-

structed with but three sections, the central 55 one in communication with a heating chamber, or with any desirable number, for example seven sections as shown in Figure 1, if desired.

Referring to Figures 1 and 3—5 inclusive 60 the radiator, embodying my invention, comprises two end sections *a*, and two intermediate sections *c*.

The intermediate sections *c* have formed on their lower ends, adjacent their opposite 65 edges, plate like members *d* which, when the sections are assembled, form a heating chamber open at the bottom. The central portions of the lower ends of the central sections *b* are cut away so that the interiors of 70 the sections *b* are in open communication with the heating chamber as shown in Figure 3.

The several sections are all provided with 75 aligning apertures *e* in their sides adjacent their upper ends, which when the sections are assembled afford communication from one section to another.

The intermediate sections *c* are provided 80 on their sides next to the central sections and adjacent their lower ends with apertures *f*, the upper portion of which align with smaller apertures *g* in the adjacent sides of the adjacent central sections *b*. The lower portions *f'* of the apertures *f* are open to the 85 atmosphere as will be noted from an inspection of Figure 3.

The end sections *a* are provided with apertures *h*, on the sides adjacent to the intermediate sections *c*, the upper portions of 90 which align with apertures *i* in the adjacent sides of the intermediate sections. The lower portions *h'* of the apertures *h* are open to the atmosphere.

The center section adjacent its lower end 95 is provided with a sight hole *j* closed with any suitable transparent material, through which the flame from a burner *k*, in the heating chamber may be observed. A hole *m* is provided through which the burner *k* may 100 be lighted by a match or taper.

Referring now to Figure 2, it may be observed that the structure therein shown is in principle the same as that above described except for the omission of the intermediate sections *c*, similar parts being similarly designated. It may further be observed that if a smaller unit be desired it

may be produced by providing but one center section.

In operation when the burner *k* is lit the air in the heating chamber and in the central sections *b* (or section) communicating therewith is heated and with the products of combustion chiefly carbon dioxide, rises in the center sections (or section) fresh air being supplied through the open bottom of 10 the heating chamber.

The heated air and products of combustion pass from the top of the center sections laterally through the apertures *e* into the intermediate sections *c* and end sections *a* 15 acting to heat those sections which, in turn, radiate the heat to the atmosphere. The heated air and products of combustion are drawn down in the intermediate and end sections by the draught in the center sections 20 created by the heated air and products of combustion rising therein.

The air and products of combustion in the intermediate and end sections tend to stratify into lighter and heavier constituents, the 25 heavier consisting mainly of cooled air passing out to atmosphere through the lower portions *f'* and *h'* of apertures *f* and *h*, while the lighter ingredients consisting of 30 products of combustion, as carbon monoxide, pass from the end to the intermediate section through the upper part of the apertures *h* and apertures *i*, and from the intermediate section to the heating chamber through the upper part of apertures *g*, all 35 as indicated by the arrows, Figure 3, to be again heated or reconsumed and recirculated.

It will now be observed that in accordance with my invention, a radiator is provided 40 which is entirely safe since it operates without the development of any substantial pressure and one in which the heated air and products of combustion are recirculated with avoidance of the passage of odors into 45 a room and with a saving of fuel.

Having now fully described my invention, what I claim and desire to protect by Letters Patent is:

1. In a heater in combination, a plurality 50 of radiating sections, a heating chamber, said sections being provided with apertures affording a passage for circulation through said sections and said heating chamber, one of the said sections being provided with an 55 aperture formed in juxtaposition to and below one of said first mentioned apertures and opening to atmosphere.

2. In a heater in combination, a plurality 60 of radiating sections, a heating chamber in communication with one of said sections, the sections being provided with apertures affording communication between the sec-

tions adjacent their upper ends, one of the sections being provided with an aperture affording communication between said section and the heating chamber and with a second aperture adjacent said last mentioned aperture and affording communication with atmosphere.

3. In a heater in combination, a plurality 70 of radiating sections, a heating chamber in communication with one of said sections, said sections being provided with apertures adjacent their upper ends affording communication between said sections, one of said sections being provided adjacent its lower end with a pair of apertures one below the other and said heating chamber being provided with an aperture aligning with one of the apertures in the lower end of said 80 last mentioned section.

4. In a heater in combination, a plurality 85 of adjacent radiating sections, a heating chamber in communication with one of said sections, a burner within the heating chamber, said sections being provided with aligning apertures adjacent their upper ends one 90 of said sections being provided with a pair of apertures positioned one above the other and affording communication with the heating chamber and with the atmosphere.

5. In a heater in combination, a plurality 95 of adjacent radiating sections, a heating chamber in communication with one of said sections, a burner within the heating chamber, said sections being provided with aligning apertures adjacent their upper ends and with aligning apertures adjacent their lower ends permitting circulation of heated air 100 through said sections and the heating chamber and with apertures adjacent to and below the aperture adjacent the lower ends of said sections, said last mentioned apertures being open to atmosphere and permitting 105 the escape of cooled air.

6. In a heater in combination, a plurality 110 of radiating sections, a heating chamber, a burner in said chamber, said sections and said chamber being provided with apertures affording communication between said sections and between said sections and said heating chamber and the atmosphere, whereby a circulation of heated air and products of combustion will be permitted between said sections and said chamber under the influence 115 of the heat from said burner, said aperture affording communication with atmosphere being positioned below the apertures affording communication between said sections and said heating chamber.

In testimony of which invention, I have hereunto set my hand, at Philadelphia, Penna., on this 18th day of September, 1925.

GILSON C. STAATS.
